UNITED STATES PATENT OFFICE.

RICHARD H. STEVENS, OF MUNHALL, PENNSYLVANIA, ASSIGNOR OF ONE-HALF TO
PER TORSTEN BERG, OF STOCKHOLM, SWEDEN.

DUMPING-CAR.

1,118,378.

Specification of Letters Patent.

Patented Nov. 24, 1914.

Application filed September 2, 1913. Serial No. 787,597.

To all whom it may concern:

Be it known that I, RICHARD H. STEVENS, a citizen of the United States, residing at Munhall, Allegheny county, Pennsylvania, have invented a new and useful Improvement in Dumping-Cars, of which the following is a full, clear, and exact description, reference being had to the accompanying drawings, forming part of this specification, 10 in which—

Figure 1 is an end view partially in section of a portion of a dumping ladle car constructed in accordance with my invention. Fig. 2 is a sectional view on the line 13 II—II of Fig. 4, showing a portion of the controlling mechanism. Fig. 3 is a similar view showing the parts in a shifted position. Fig. 4 is a sectional view on the line IV—IV of Fig. 3. Fig. 5 is a view similar 20 to Fig. 1 showing a modified form of controlling mechanism. Fig. 6 is a detail end view of the rack of the controlling mechanism, and Fig. 7 is a sectional view on the line VII—VII of Fig. 5.

25 My invention relates to dumping cars, more particularly dumping ladle cars employed in handling and transporting molten materials such as iron or blast furnace, slag or cinder, and which are tipped or tilted when being dumped of their contents.

The main object of my invention is to provide an improved device for controlling the dumping movement of the ladle.

By the use of my invention a slow dumping movement may be imparted to the ladle. At the end of the movement, a rapid oscillating motion may be imparted to strike the ladle forcibly on the frame of the car to dislodge the skull.

30 The precise nature of my invention will be best understood by reference to the accompanying drawings which will now be described, it being premised, however, that various changes may be made in the details 45 of construction and general arrangement of the parts without departing from the spirit and scope of my invention, as defined in the appended claims.

In the drawings, the numeral 2 designates 50 a ladle or cinder pot of a cinder car, secured in place in the usual trunnion ring forming part of the trunnions 3, by which the ladle is mounted upon the frame 4 of the car. The trunnions 3 are each provided with a trunnion gear 5 having teeth meshing with simi-

lar gear teeth on the trunnion gear racks 6. One of the trunnion gears 5 is provided with lugs 7, 7^a, to one of which one end of a link is connected. This link 8 is pivotally connected at its central portion to a cross-head 9, as indicated at 10.

11 is a piston rod connected to the cross-head 9 at the one end, the other end being provided with a piston 12 within a cylinder 13.

14 are the actuating connections for the cylinder 13 which are controlled by means of a valve mechanism, indicated at 15.

When the parts are connected as indicated in Fig. 1, the piston is moved to the right 70 to dump the ladle which is rocked by means of the various connections in the direction indicated by the arrow. If it is desired to dump the ladle in the reverse direction, the link 8 is disconnected from the lug 7 and 75 the piston 12 is moved to the other end of the cylinder. The opposite end of this link 8 is then connected to the lug 7^a, so that the ladle will be dumped when the piston is moved to the left and returned to its upright 80 position when moved to the right.

All of the foregoing mechanism is old and well known to the art and forms no part of my invention.

Journalized in the supporting frame of the 85 dumping mechanism is a shaft 16, and connected to this shaft is a gear wheel 17 which is in mesh with the teeth of a rack 18 connected to the cross-head so as to reciprocate therewith.

90 19 is a skew gear connected to the shaft 16 and in mesh with a skew gear 20 on a shaft 21 journaled in a frame or casing 22. Surrounding the shaft 21 between the skew gear 20 and the casing 22 are springs 95 23, 23^a.

The mechanisms in Figs. 1 and 2 are in the positions to which they have been brought when the ladle was moved to its upright position after the last dumping action. When it is desired to dump the ladle, pressure is admitted into the left hand end of the cylinder 13 to move the piston to the right, and during the first movement of the piston the skew gear 20 will be moved 105 to the left and compress the spring 23 in the left hand side of the casing 22. As soon as the resistance of the spring is greater than the frictional engagement between the gears 19 and 20, the gear 20 will 110

rotate and act as a brake during the dumping movement. When the ladle has moved its full extent so that it engages the usual stop at the end of its movement, pressure 5 to the left hand end of the cylinder is cut off. If there is a skull to be dislodged, pressure is admitted to the right hand end of the cylinder 13 to move the parts in a reverse direction for a short distance, but 10 not sufficiently to take up the lost motion between the gear 20 and spring 23^a. The pressure is then again reversed to move the piston toward the right, which will move the ladle downwardly very rapidly so that 15 it will strike the ladle stop a sharp blow before the brake is brought into action to dislodge the skull. The length of this rapid movement may be varied by changing the length of the lost motion between the 20 springs and the gear 20. By varying the pitch of the gears 17 and 20 as well as the size of the springs, the speed of the dumping action can be changed. It will readily be understood by those familiar with the 25 art that the strength of the springs as well as the angle of the gears 17 and 20 must be varied in accordance with the load to be handled, and in accordance with the speed at which the load is to be moved.

30 In Figs. 5 to 7, I have shown a modified form of frictional controlling mechanism in which I have applied the same reference numerals to similar parts. In this construction I mount a worm-wheel 24 in bearings on the cross-head 9. This worm-wheel is arranged to rotate within these bearings and is also permitted to reciprocate a predetermined distance as hereinafter described. Extending upwardly from the car 35 frame are uprights 25 at each side of the car and at one end thereof. Mounted in each of these uprights are pins 26, and 27 is a worm-rack which is arranged to reciprocate on these pins and which is also 40 in mesh with the worm 24. Surrounding these pins and interposed between the ends of the worm rack and uprights 25 are springs 28 which perform the same function as the springs 23, 23^a in the structure 45 previously described. In this construction the cross-head 9 can move to the right until the lost motion is taken up between the points a—a and as soon as this lost motion is taken up the springs at the right hand 50 end will be compressed until their resistance is equal to the frictional resistance between the worm and its rack. As soon as this resistance is reached the worm will be rotated and act as a brake during the 55 dumping movement.

60 The advantages of my invention result from the provision of a frictional brake for controlling the speed during the dumping action, and which is arranged to permit the 65 mechanism to move freely in the reverse

direction a predetermined distance and then move forward the same distance without the brake acting to resist the movement.

I claim:

1. A dumping car, a motor geared to said car to effect the dumping movement thereof, an automatic brake device for controlling the movement of the motor, and means for permitting the motor to reverse and then move forward a predetermined distance at 75 any point of the dumping movement without bringing the braking device into action; substantially as described.

2. A dumping car, a motor geared to said car to effect the dumping movement thereof, 80 a resilient braking device for controlling the movement of the motor during the dumping, and means for permitting the motor to reverse and then move forward a predetermined distance at any point of the 85 dumping movement without bringing the braking device into action; substantially as described.

3. A dumping car having a motor geared thereto to effect the dumping movements thereof, a brake device comprising a rotary friction member for controlling the dumping movement, and means for permitting said rotary device to move longitudinally a predetermined distance to permit the motor 90 to move a slight distance without bringing the brake device into action; substantially as described.

4. In a dumping car, an actuating motor, 100 actuating connections between the car and the motor to effect the dumping movements thereof, and frictional gearing in said actuating connections, said frictional gearing being arranged to permit the actuating connections to move a slight distance before 105 the frictional gearing is brought into operation; substantially as described.

5. A dumping car having a ladle pivoted thereto, an actuating motor for dumping said ladle, actuating connections between 110 the motor and the ladle, and frictional gearing in said actuating connections, said frictional gearing being arranged to permit the motor to move a slight distance before the frictional gearing is actuated; substantially 115 as described.

6. A dumping car having a ladle pivoted thereto, a motor for dumping said ladle, actuating connections between the ladle and the motor, skew gears in said actuating connections, and means for permitting one of 120 said gears to move longitudinally a predetermined distance before it is rotated; substantially as described.

7. A dumping car having a ladle pivoted thereto, a motor for dumping said ladle, actuating connections between the ladle and the motor, skew gears in said actuating connections, and means for permitting one of 125 said gears to move longitudinally a prede- 90

terminated distance before it is rotated, together with yielding means at each end of the reciprocating skew gear; substantially as described.

5 8. A dumping car having a tiltable ladle, and a motor for actuating the ladle, and actuating connections between the motor and ladle having means for causing a slow motion of the ladle during the dumping operation, and for then permitting a relatively short and quick backward and forward movement without bringing said means for causing a slow motion of the ladle into action.

15 9. A dumping car, a motor to effect the dumping movement thereof, and a brake device having frictional surfaces in engagement with each other for controlling the dumping movement; substantially as described.

20 10. A dumping car, a motor to effect the dumping movement thereof, and an automatic brake device having frictional surfaces in engagement with each other for controlling the dumping movement; substantially as described.

25 11. A dumping car, a resilient friction brake for controlling the dumping movement, a motor geared to said car to effect the dumping movement thereof, and means for permitting the motor to move a predetermined distance backward and then forward at the end of the dumping movement independent of the brake device; substantially as described.

30 12. In a dumping car, a motor for the dumping movement thereof, a brake device for controlling the dumping movement, and means for permitting the motor to reverse and then move forward a predetermined distance at any point in the dumping movement without bringing the brake device into action; substantially as described.

35 13. A dumping car, a motor to effect the dumping movement thereof, a brake device 45 having frictional surfaces in engagement with each other for controlling the dumping movement and means for permitting the motor to move a predetermined distance without bringing the brake device into 50 action; substantially as described.

14. A dumping car, a motor to effect the dumping movement thereof, an automatic brake device having frictional surfaces in engagement with each other for controlling 55 the dumping movement and means for permitting the motor to move a predetermined distance without bringing the brake device into action; substantially as described.

15. A dumping car, a motor to effect the 60 dumping movement thereof, a resilient brake device having frictional surfaces in engagement with each other for controlling the dumping movement and means for permitting the motor to move a predetermined distance 65 without bringing the brake device into action; substantially as described.

16. A dumping car having a motor to effect the dumping movements thereof, a brake comprising a plurality of members 70 having frictional surfaces arranged to engage each other for controlling the dumping movement, one of said members being arranged to move longitudinally a predetermined distance before its frictional surface 75 is brought into engagement with the frictional surface of the other member to permit the motor to move a slight distance without bringing the brake into action; substantially as described.

80 In testimony whereof, I have hereunto set my hand.

RICHARD H. STEVENS.
